(57) **CLAIM**

We claim the ornamental design for a multi-function printer, as shown and described.

DESCRIPTION

FIG. 1 is a front perspective view of a multi-function printer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the multi-function printer are for environmental purposes only and form no part of the claimed design.

1 Claim, 7 Drawing Sheets
